Attorney

UNITED STATES PATENT OFFICE.

WILLIAM L. NOBLITT, OF SHELBY, NORTH CAROLINA, ASSIGNOR OF ONE-HALF TO
WILLIAM N. DORSEY, OF SHELBY, NORTH CAROLINA.

LOOM-CLEANING DEVICE.

Application filed October 3, 1922. Serial No. 592,061.

To all whom it may concern:

Be it known that I, WILLIAM L. NOBLITT, a citizen of the United States, residing at Shelby, in the county of Cleveland and State 5 of North Carolina, have invented certain new and useful Improvements in Loom-Cleaning Devices, of which the following is a specification.

This invention relates to new and useful 10 improvements in loom cleaning devices and is especially designed to clean the filling fork grate on weaving looms.

It is a well known fact to those skilled in the art to which this invention appertains, 15 that when the filling fork has dust or lint on it, it causes thin places in the fabric. Through the use of my invention, the filling fork is kept free of dust, dirt or lint accumulations and hence the above objects are 20 overcome or eliminated.

My device is also a great labor saving instrument as the cleaning of the filling fork has heretofore been done by hand.

With the foregoing and other objects in 25 view that will appear as the nature of my invention is better understood, the same consists in the novel features of construction, combination and arrangement of parts illustrated in the drawings and more especially 30 pointed out in the appended claim.

In the accompanying drawings, which are for illustrative purposes only and are therefore not drawn to scale:

Figure 1 is an elevational view, partly in 35 section, illustrating the application of my invention.

Figure 2 is a detail perspective view of the cleaning device and Figure 3 a detail longitudinal section.

40 Referring to the drawings for a more particular description of my invention, and in which drawings like parts are designated by like reference characters throughout the several views, A designates the frame of a weaving loom, B the drive shaft, C the pitman and D the filling fork grates. The above parts are of any ordinary or approved construction and hence, no further explanation in this regard is required.

45 E designates the cleaning device, as a

whole. Specifically, this device comprises the brush 1, supporting bracket 2 and connecting link 3. The bracket 2, which is substantially of L-shape form, is provided in its depending leg 4 with a longitudinal slot 5. 55 This leg is adjustably secured to the upper end of the oscillating lever or bar 6, pivoted, as at 7, to the weaving loom frame A and connected at its lower end by the crank 8 and cam or eccentric 9, with the drive 60 shaft B. The above adjustment is accomplished by the bolt 10 carried by the upper end of the bar 6 and the nut 11 screwing on the threaded end of said bolt. The outer end of the upper leg 12 of the supporting bracket 65 is connected by the bolt and nut 13 and 14, respectively, with the inner end of the connecting link 3. The brush 1 is carried by the outer end of the link 3 and may be adjusted back and forth thereon by the bolt 15 extending through an elongated longitudinal slot 16 in the link and through a corresponding transverse opening 17 in the brush head 18. The parts are so timed that the brush 1 moves in an arc along the tines of the fork 70 when the fork arrives at the outer end of the arc of its path of movement and as indicated in Figure 1 of the drawing, which keeps the same free of any dust, dirt or lint accumulations. The brush may be advanced from 75 time to time as the bristles become worn in order that it may perform its work efficiently. This adjustment is permitted by virtue of the adjustable connection between the brush and connecting link 3. 80

85 From the foregoing description taken in connection with the drawings, it is thought that the construction, operation and advantages of my invention will be readily understood without requiring a more extended explanation.

Having described my invention, what I claim as new and desire to secure by Letters Patent, is:—

90 In combination with a weaving loom having a driving shaft, a filling fork grates mounted for movement in an arc disposed transversely of the axis of the shaft, means operatively connecting the fork grates with the shaft, a fork grates cleaning device com-

prising a lever fulcrumed to the frame of the loom, means connecting the lever with the shaft and adapted to impart oscillatory movement to the lever, a bracket carried at the free end of the lever, a brush, a flat link connected at its inner end with one arm of the bracket and a slot and bolt connection between the outer end of the link and the

brush whereby the latter may be advanced toward the filling fork grate, the parts being so arranged and timed that the brush moves in an arc along the tines of the fork when the fork grate arrives at the outer end of the arc of its path of movement.

In testimony whereof I affix my signature.
WILLIAM L. NOBLITT.
